UNITED STATES PATENT OFFICE

111,601

DESIGN FOR A TEXTILE FABRIC

Harry M. Goldman, New York, N. Y.

Application July 6, 1938, Serial No. 78,293

Term of patent 3½ years

To all whom it may concern:

Be it known that I, Harry M. Goldman, a citizen of the United States of America, residing in the city of New York, county of New York, and State of New York, have invented a new, original, and ornamental Design for a Textile Fabric, of which the following is a specification, reference being had to the accompanying drawing, forming part thereof.

The drawing shows substantially one-half the length of the fabric the upper half beginning with the upper horizontal line being the same but

arranged in reverse order to complete the length of the fabric.

The figure on the drawing is a plan view of a textile fabric showing my new design. The design unit is contained between the dot and dash lines which unit is repeated in regular succession as indicated by the extensions beyond the unit boundaries.

I claim:

The ornamental design for a textile fabric, substantially as shown and described.

HARRY M. GOLDMAN.
